DOUBLE LOCK

James E. Phillips, New York, N. Y.

Application February 15, 1941, Serial No. 379,061

2 Claims. (Cl. 292—338)

This invention relates to a device which is designed and adapted to prevent a person from making a wrongful entry after jimmying a lock on a door or other closure element, and also to frustrate such entry by the use of force and other improper and unlawful methods.

An object of the invention is the provision of a device of the indicated character which may be used advantageously in conjunction with a conventional or standardized lock applied to a closure element such as a door, without affecting the usual operation of the lock, and requiring only a simple operation to employ the device for the intended purposes aforesaid.

With the foregoing and other objects in view the invention resides in the combination, construction and functions of the parts hereinafter described and illustrated in the accompanying drawing in which:

Fig. 1 is an inside view and part section showing portions of a hinged door, the jamb of the door and a floor, a conventional lock and its keeper secured to the door and jamb respectively, in combination with a device embodying the features of the invention;

Fig. 2 is a vertical section taken on the line 2—2 of Fig. 1;

Fig. 3 is a horizontal section taken on the line 3—3 of Fig. 1;

Fig. 4 is a horizontal section through the door showing both jambs, a portion being broken away, and illustrating the anti-jimmying feature of the device;

Fig. 5 is a detached perspective view of the slide of the lock and one of the rod keeper members connected therewith;

Fig. 6 is a view somewhat similar to Fig. 1, but showing a modification of the device;

Fig. 7 is a section taken on the line 7—7 of Fig. 6;

Fig. 8 is a detached perspective view of the slide of the lock shown in Fig. 6, but showing the modified attachment of one of the rod keeper members.

Referring now more particularly to Figs. 1 to 5 inclusive it will be apparent that one form of the device is applied in conjunction with a hinged door, one jamb of the door and an apartment floor in proximity to the door. Only portions of these parts are shown, the door being designated 10, the jamb 11 and the floor 12. A conventional lock 13 is secured to the door and the keeper 14 of the lock is secured to the jamb 11. The lock 13 is key-operated from the outside of the door and knob-operated from the inside 55

thereof. It is to be understood that any other suitable lock may be used. The device of the present invention is employed in conjunction with a movable part of the lock which functions in the usual locking and unlocking operations. Said part 15 is best shown in Fig. 5 and is in the form of a slide which is actuated by key or by the knob 16 to project the bolts 17 to locking position into the keeper 14 and to retract them therefrom to the unlocking position.

The device consists of cooperative keeper members 18, 19 and 20 respectively and a rigid rod or bar 21. The members 18 and 19 cooperate to engage and release the upper end of the rod 21 and the member 20 accommodates the lower end of the rod in a manner and for a purpose to appear. The keeper member 18 is open-sided or has a semi-cylindrical keeper portion 22 and a rod 23 rigidly connected with the portion 22 and extending laterally therefrom, said rod 23 being secured in a practical manner to the slide 15, the casing of the lock having a hole 24 therein through which the rod 23 extends. The portion 22 is disposed at all times exteriorly of the lock casing. The keeper member 19 consists of a plate 25 and abutments 26 and 27 respectively integral with the plate 25. The abutment 26 consists of portions 28, 29 and 30 respectively. The portion 28 is flat and merges into the portion 29 which is semi-cylindrical and the portion 29 joins the portion 30 which in turn joins the plate 25. The portions 28 and 29 are spaced from the plate 25 in parallel relation thereto with respect to the vertical axis of the plate 25, whereas the portion 30 is disposed at a right angle with respect to the plate. The abutment 27 has a notch 31 which registers with the semi-cylindrical portion 29 and the abutment 27 is disposed at right angles to the plate and portions 28 and 30. The keeper member 19 thus constructed is open at the left side and the bottom. The member 19 is fixedly secured to the door by suitable fastening elements such as the screws 32 which extend through plate 25 and have the heads thereof bearing on the plate. The member 19 is juxtaposed with respect to the member 18 so that the portion 22 may move inwardly to a position in which it registers with the notch 31 as the bolts 17 of the lock are retracted and outwardly to a position in which it is disposed directly beneath the abutment portion 28 when the bolts 17 of the lock are projected into the keeper 14. The keeper member 20 consists of a socket which is received in a suitable recess in the floor 12, the member being held in place by a screw 33 driven

into the floor. The rod or bar 21 is of suitable length to reach the keeper member 18 and the socket member 20 and is bent somewhat as at 34 in order to slant downwardly from the member 18 to the member 20 to effectually hold the door against unintentional inward movement.

From the foregoing it will be apparent that when the lock 13 is unlocked, the slide 15 is in retracted position which brings the keeper portion 22 in registry with the notch 31. The rod 21 then may be put in place by canting it and engaging its upper end with the portion 22. The notch 31 permits upward movement of the rod 21 to bring the lower end of the latter directly over the socket member 20, after which the rod 21 may be moved downwardly to put the lower end thereof in the socket member 20. The socket member 20 is large enough to allow the rod 21 to be canted sidewise from the position shown in dot-and-dash lines to the position shown in full lines, and vice versa, as the slide 15 is being actuated to either lock or unlock the door. When the slide 15 is in the locking position to project the bolts 17, the keeper portion 22 and the upper end of the rod 21 engaged with the latter will be disposed directly beneath the abutment 27 and opposite the abutment portion 28. The rod 21 will then be locked in a door holding position against displacement by the three members 18, 19 and 20 under control of the lock 13. If the lock is jimmied it will still be impossible for a person on the outside to swing the door 10 inwardly on its hinges 35 to open position. If the lock is unlocked by the use of a key from the outside, the rod 21 will merely assume the position shown in dot-and-dash lines in Fig. 1 which is also a door-holding position and it will be impossible still to swing the door inwardly to open position. When the rod 21 is in the position shown in dot-and-dash lines its upper end will encounter the abutment portion 29 in an attempt to open the door from the outside, while the door is unlocked. The rod 21 in this position may be removed by first moving the same upwardly through the notch 31 until the lower end of the rod clears the socket member 20, after which the rod may be canted sufficiently and then be fully disengaged to permit the door to be opened and closed at will.

A strip 36 integral with the keeper member 19 or as a separate part is secured to the door 10 on the inside thereof. This strip has the end bent into an L-shape portion 37 which is received between the door and the jamb 38 and extends into a recess 33 in the jamb when the door is closed to prevent jimmying or forcing of the door from connection with its hinges 35.

In Figs. 6, 7 and 8 there is shown a modifica-

tion of the cooperative keeper members for the upper end of the rod 21. In this form of the invention the lock 40 is standardized to include a keeper member 41 equivalent to the member 18 in which the member 41 will be integral with or be attached as at 42 to the slide 15'. The casing 43 of the lock has a slot 44 so that the member 41 may extend downwardly from the slide. The casing 43 has a keeper member 45 integral therewith which is the equivalent of the member 19 in that it provides an abutment portion 46 comparable to the portion 29. The casing 43 also serves as an abutment comparable to the abutment 27. In other respects this form of the invention is similar to that shown in Figs. 1 to 5 inclusive and is productive of the same results.

I claim:

1. A locking device including a primary lock having a reciprocable locking bolt, a semi-cylindrical rod-engaging member carried by said bolt, and a fixed keeper positioned to cooperate with said member, said keeper being open at the bottom and having an abutment at the top, a second abutment at the front and an opening in the top abutment, said abutments and the opening being positioned with respect to said member to hold a brace rod from being canted when the locking bolt is in its locking position by reason of the upper end of said rod being engaged in said member and the top abutment and front abutment being disposed at the top and the side respectively of said upper end, and to release said rod so that it may be removed when said bolt is in its unlocking position by reason of said member being in alignment with said top opening.

2. A locking device comprising a primary lock having a casing and a reciprocable locking bolt; an open-sided rod-engaging member secured to one end of said bolt and extending through said casing, and a separate fixed keeper positioned to cooperate with said member, said keeper being open at the bottom and having a top abutment, a front abutment and an opening in the top abutment, said abutments being cooperatively positioned with respect to said rod-engaging member to hold a brace-rod in functioning position when the locking bolt is in its locking position by reason of the upper end of said rod being engaged in said member and the top abutment and front abutment being disposed at the top and the side respectively of said upper end, and to permit said rod to be moved upwardly in said opening and then be canted so that it may be removed when said bolt is in its unlocking position by reason of said member being in alignment with said top opening.

JAMES E. PHILLIPS.
